FLUID POWER CYLINDER

Charles Doolittle, Lexington, Ky., assignor to Westinghouse Air Brake Company, Wilmerding, Pa., a corporation of Pennsylvania

Filed Mar. 14, 1966, Ser. No. 1,449

Term of patent 14 years

(Cl. D55—1)

FIG. 1 is an isometric view of a fluid power cylinder, showing my new design;

FIG. 2 is a fragmentary isometric view of the fluid power cylinder shown in FIG. 1, and showing a modified end portion thereof;

FIG. 3 is a fragmentary isometric view of the fluid power cylinder shown in FIG. 1, and showing another modified end portion thereof.

The right end of each cylinder of FIG. 1, FIG. 2, and FIG. 3 is similar to the end shown on the corresponding cylinder.

The dominant features of my design reside in those portions shown in full lines.

I claim:

The ornamental design for a fluid power cylinder, as shown and described.
